LATCH COVER FOR A FISHING TACKLE BOX OR SIMILAR ARTICLE

Richard G. Woolworth, Lancaster, Pa., assignor to Wood-stream Corporation, Lititz, Pa., a corporation of Pennsylvania

Filed Apr. 18, 1967, Ser. No. 6,748

Term of patent 14 years

(Cl. D50—7)

FIG. 1

FIG. 3

FIG. 2

FIG. 4

FIG. 5

FIG. 6

FIGURE 1 is a perspective view of a latch cover for a fishing tackle box or similar article;

FIGURE 2 is a front view of the latch cover;

FIGURE 3 is an end view of the latch cover;

FIGURE 4 is a rear view of the latch cover;

FIGURE 5 is a top plan view of the latch cover; and FIGURE 6 is a bottom plan view of the latch cover. The box shown in broken lines in FIGURE 1 is included for illustrative purposes only.

I claim:

The ornamental design for a latch cover for a fishing tackle box or similar article, as shown and described.
